UNITED STATES PATENT OFFICE

LEON E. SIMMONS, OF CLAREMONT, NEW HAMPSHIRE, ASSIGNOR TO SULLIVAN MACHINERY COMPANY, A CORPORATION OF MASSACHUSETTS

MINING MACHINE

Application filed December 24, 1930. Serial No. 504,610.

This invention relates to mining machines, and more particularly, but not exclusively, to coal mining machines of the shear cutter type adapted to cut vertical kerfs in the coal.

5 An object of this invention is to provide an improved coal mining machine. Another object is to provide an improved coal mining machine of the wheel mounted, track supported type adapted to insert vertical or shear cuts in the coal. Still another object of this invention is to provide an improved mining machine of the wheel mounted, track supported type having improved kerf cutting mechanism and improved means for operating the cutting mechanism, for guiding the cutting mechanism during the cutting operation, and for propelling the machine about the mine. A still further object is to provide an improved shearing machine of the 15 self-propelled, truck mounted type wherein improved means are provided for moving and guiding the shear cutting mechanism relative to the truck during the cutting operation, for positioning the cutting mechanism 20 relative to the coal face and for propelling the truck along the mine trackway during transport. Yet another object of this invention is to provide an improved coal mining machine of the wheel mounted track supported type having a guideway for guiding the cutting mechanism during the cutting operation and having associated therewith improved power operated means for adjusting the guideway relative to the truck. A 25 still further object is to provide an improved coal mining machine wherein a guideway is employed for guiding the cutting mechanism during the cutting operation and having improved power operated means for feeding the cutting mechanism along the guideway and for swinging the guideway relative to the truck. These and other objects of the invention will, however, hereinafter more fully appear.

45 The invention is exemplified in the novel combinations and arrangements of parts shown in the accompanying drawings, and described in the following specification, and as more particularly pointed out in the appended claims.

In the accompanying drawings there is shown for purposes of illustration one form which the invention may assume in practice.

In these drawings,—

55 Fig. 1 is a plan view of an illustrative embodiment of the improved mining machine;

Fig. 2 is a side elevational view of the machine shown in Fig. 1;

Fig. 3 is an enlarged fragmentary side elevational view of the machine shown in Fig. 2;

Fig. 4 is a transverse vertical sectional view taken substantially on line 4—4 of Fig. 2;

Fig. 5 is a detail sectional view taken substantially on line 5—5 of Fig. 4;

Fig. 6 is a transverse vertical sectional view taken substantially on line 6—6 of Fig. 2;

Fig. 7 is a horizontal sectional view taken substantially on line 7—7 of Figs. 2 and 3;

Fig. 8 is a detail sectional view taken substantially on line 8—8 of Fig. 4;

Fig. 9 is a transverse vertical sectional view taken substantially on line 9—9 of Figs. 2 and 3;

Fig. 10 is a detail sectional view taken on line 10—10 of Fig. 9;

Fig. 11 is a detail sectional view illustrating the locking mechanism for preventing tilting and lateral movement of the guiding frame; and

Fig. 12 is a detail view illustrating the lock or stop member for holding the sliding support for the cutting mechanism in its rearmost position on the guiding frame.

In this illustrative embodiment of the invention there is shown a coal mining machine of the wheel mounted shear cutter type adapted to operate while supported by a mine trackway and herein of the same general type as that disclosed in the copending application to Morris P. Holmes, Serial No. 467,791, filed July 14th, 1930, with certain modifications and improvements embodied therein as hereinafter described.

This machine generally comprises a 95 wheeled truck 1, an elongated swiveled guiding frame 2 arranged horizontally on the truck and having an adjustable front support, kerf cutting mechanism generally designated 3, truck propelling mechanism 4 and the im- 100

proved mechanism 5 for moving the cutting mechanism along the guiding frame 2 and for swiveling the guiding frame horizontally relative to the truck. The guiding frame 2 is 5 mounted at the forward end of the truck for horizontal swinging movement relative thereto about a vertical axis 6. The guiding frame 2 is adapted to be swiveled into different angular positions relative to the truck 10 and the kerf cutting mechanism is guided for movement longitudinally of the guiding frame during the cutting operation, and the cutting mechanism is adapted to drive, when in its transport position on the truck, the 15 truck propelling mechanism 4.

Now referring to the wheeled truck 1, it will be observed that the same herein comprises a truck frame 7 supported by wheels 8 adapted to travel along a mine trackway 9. 20 Supported at the forward end of the truck frame 7, herein directly above the front truck wheel axle as shown in Fig. 4, is a horizontal swivel plate 10 having secured thereto, beneath the same, an annular frame or swivel bearing 11 carrying series of horizontal and vertical rollers 12 and 13 journaled on pins 14 and 15 respectively, carried by the frame 11. The horizontal rollers 12 engage the inner periphery of an annular guide or bearing housing 16 secured to the angle members 17 of the truck frame while the vertical rollers engage the upper surface of a horizontal plate 18 likewise secured to the angle members 17 of the truck frame. These elements 30 form a horizontal turntable structure on which the guiding frame 2 is mounted for horizontal swinging movement relative to the truck. As shown in Figs. 2 and 4, rigidly attached to the swiveled plate 10 at the outer 35 sides thereof are angle members 19, 19 having vertical flanges rigidly secured to the depending flanges of the parallel longitudinal extending angle members 20, 20 of the guiding frame 2. These angle members 20, 20 extend 40 a substantial distance forwardly and rearwardly of the turntable structure with the rearwardly extending portions thereof overlying, when the parts are in the position shown in Fig. 1, the truck. 45

50 Any suitable means may be employed for holding the elongated guiding frame 2 against vertical tilting movement and lateral swinging movement relative to the truck when the guiding frame is in the position shown 55 in Fig. 1, i. e., the transport position, and for illustrative purposes are shown as herein comprising a transverse supporting member or support abutment 22 carried by the truck and on which the rear end of the guiding frame 2 rests when the frame is in its central 60 longitudinal position shown. Suitably journaled within bearings carried by the angle members 17 of the truck frame is a transverse rod 23 having secured thereto an operating handle 24. Also attached to this rod are ver-

tical stop plates 25, which, when the parts are 70 swung in the position shown in Fig. 11, engage the outer surfaces of the depending flanges of the angle members 20, 20 of the guiding frame, and these stop members, when so positioned, prevent lateral swinging movement of the guiding frame relative to the truck. When these stop members are swung downwardly out of engagement with the 75 guiding frame, the latter may be swung horizontally relative to the truck as hereinafter to be described. To prevent vertical tilting movement of the guiding frame relative to the truck, there is provided in one of the stop plates 25 a slot 26 adapted to 80 engage a projecting pin 27 secured to one of the angle members of the guide frame, and this slotted member and pin cooperate to hold the guiding frame down in position against the transverse support abutment 22. A suitable latch 28 carried by the stop plate which is slotted, is adapted releasably to cooperate with the pin 27 to hold the stop plates in position.

85 The guiding frame 2 forms an elongated guideway or track for the kerf cutting mechanism 3 along which the latter moves during the cutting operation, and this kerf cutting mechanism includes a frame or sliding support 30 having guide plates or shoes 31 attached to the lower portion thereof for slidably engaging the upper plane surfaces of the horizontal flanges of the angle members 20, 20 of the guide frame. The frame or support 30 has a depending portion presenting parallel lateral guide surfaces 32, 32 engaging the inner vertical surfaces of the angle members 20, 20, as shown in Fig. 4. For holding the sliding support 30 in position on the guiding frame, that is, to prevent vertical displacement of the support from the guide, there are provided angle members 33 secured to the sides of the support 30 and having inwardly projecting horizontal flanges underlying the outwardly extending horizontal flanges of the angle members 20, 20 of the guiding frame. It will 95 thus be seen that the structure described above forms a sliding support for the kerf cutting mechanism and is slidable longitudinally of the guiding frame between the ends thereof, as hereinafter described.

100 Now referring to the kerf cutting mechanism, and more particularly to the driving mechanism for the cutting mechanism, it will be observed that mounted upon the sliding frame 30 at the rear thereof, as clearly shown in Fig. 7, is a horizontal motor 34 having its power shaft 35 horizontally disposed and extending transversely of the support. Attached to one end of the motor power shaft is a spur pinion 36 meshing with an intermediate or idler gear 37 journaled on a stub shaft 38 suitably supported within a gear housing 39 attached to one side of the sup-

port 30. This idler gear 37 meshes with a spur gear 40 keyed to a horizontal shaft 41 arranged parallel with the motor shaft and suitably journaled within bearings 42 carried by the support 30. Herein formed integral with the shaft 41, at the opposite end thereof from the spur gear 40, is a spur pinion 43 meshing with a large spur gear 44 which herein constitutes the main driving gear for the cutting mechanism. This gear has a hub portion 45 mounted on a horizontal transversely extending shaft 46 arranged parallel with and in advance of the shaft 41. Surrounding the hub 45 of the gear 44 is a sleeve 47 which also forms a part of the bearing structure for the driving parts. Secured to the hub 45 by bolts 48 is the hub of a bearing member 49 supporting a bearing sleeve 50 on which a chain sprocket 51 is journaled. This chain sprocket is connected by a semi-permanent clutch 52 to the sleeve 47 and engages and drives an endless cutter bit carrying cutter chain 53 mounted for orbital movement on the margin of an elongated plane cutter bar 54. This cutter bar is adapted to swing in a vertical plane and is arranged to move in planes at one side of the guiding frame 2, as shown in Fig. 1. In the present construction the cutter bar 54 is provided with an annular hub portion 55 supported for rotative movement within a bearing sleeve 56 suitably carried by the support 30. Also attached to the outer surface of the cutter bar is a plate 57 which is attached to a cylindrical bearing member 58 rotatably supporting the outer extremity of the transverse shaft 46. Secured to a flange-like portion of the hub 55 secured to the cutter bar is a frame member 59 in turn secured to a bearing member 60 rotatably mounted in a bearing sleeve 61 likewise mounted within the support 30. It will thus be seen that the frame members 55, 58 and 60 form a horizontal pivotal support for the cutter bar. As illustrated, the spur gear 44 is connectible to the sleeve 47, to which the chain sprocket 51 is connected, by means of a sliding pin clutch 62 including clutch pins 63 slidably mounted in apertures 64 formed in the hub of the gear 44. These pins when in their connected position (as shown in Figs. 4 and 7) project within sockets 65 formed in the inner surface of the bearing sleeve 47. For sliding the clutch pins in and out there is provided reciprocable shipper members 66 guided within suitable bores formed within the bearing frame 60 and interlocked at their outer ends with inwardly projecting flanges formed on the clutch pins 63. The members 66 are attached to an annular shipper member 67 having any suitable shifting means. It will thus be seen that when the pin clutch 62 is in its connected position as shown in Fig. 4, the cutter chain 53 may be operatively connected to the motor through the spur gearing 36, 37, 40, 43

and 44. Upon release of the pin clutch 62 the cutter chain may remain idle during running of the motor.

In specifically describing the improved mechanism for swinging the cutter bar about its pivotal axis, it will herein be noted that the hub 45 (see Figs. 4 and 7) is keyed to the shaft 46 and drives the latter. This shaft is journaled within a bearing sleeve 68 supported within the cutter bar support 60 and has fixed thereto at its inner end a bevel pinion 69 meshing with reverse bevels 70 and 71. These reverse bevels are journaled on bearings supported by a vertical shaft 72 in turn journaled within bearings carried by the sliding support 30. The reverse bevels 70, 71 are selectively connectible to the shaft 72 by multiple disc clutches 73 and 74 respectively, having suitable operating means so that when one is applied the other is released. The lower end of the vertical shaft 72 is keyed to an alined shaft 75 suitably journaled within the support 30. Keyed to the shaft 75 is a clutch member 76 which is connectible by a sliding dental clutch 77 to a clutch member 78 keyed to a worm 79. When the clutch 77 is connected the worm 79 is driven at a relatively high speed directly by the shaft 72 and in either of opposite directions under the control of the clutches 73, 74. To effect drive of the worm 79 at a relatively slow speed there is formed integral with the shaft 72 a spur pinion 80 meshing with a spur gear 81 keyed to a vertical shaft 82 arranged parallel with the shaft 75 and likewise suitably journaled within the support 30. Keyed to the lower end of the shaft 82 is a spur pinion 83 meshing with a spur gear 84 arranged coaxially with the shaft 75 and suitably journaled within the support 30. Keyed to the hub of the gear 84 is a clutch member 85 which is connectible by a sliding dental clutch 86 to a clutch member keyed to the worm 79. It will thus be seen that when the clutch 86 is connected and the clutch 77 released, the worm 79 may be driven in either of opposite directions, under the control of the reverse clutches 73, 74, at a relatively low speed through the spur gearing 80, 81, shaft 82, spur gearing 83, 84. The worm 79 meshes with a worm wheel 87 (see Fig. 6) keyed to a horizontal shaft 88. This shaft extends transversely of the support 30 parallel with the shafts 41, 46 and is likewise suitably journaled within the support. Herein, formed integral with the shaft 88 is a spur pinion 89 meshing with an intermediate or idler gear 90 suitably journaled on a stub shaft 91 supported by the frame 30. The idler gear 90 meshes with the teeth of a gear segment or arcuate rack 92 herein formed integral with the frame 59 secured to the pivotal supporting frames 55, 60 for the cutter bar 54. From the foregoing description it will be evident that the cutter bar 54 may be swung in either of opposite directions

at a relatively high bar positioning speed or at a relatively slow speed appropriate for cutting.

Now referring to the improved motor operated mechanism for swinging the guiding frame 2 relative to the truck and for moving the cutting mechanism 3 forwardly and rearwardly along the guiding frame, it will herein be noted that keyed to the shaft 82 is a clutch member 93 connectible by a sliding dental clutch 94 to a clutch member 95 secured to a worm 96. This worm is suitably journaled on the shaft 82 and meshes with a worm wheel 97 (see Fig. 6) keyed to a horizontal shaft 98 alined with the shaft 88 and likewise suitably journaled within the support 30. Herein formed integral with the shaft 98 at the outer end thereof and enclosed within a depending portion 99 of the gear housing 39 is a feed operating member 100, herein in the form of a chain sprocket directly engaging a flexible feeding element 101, herein in the form of a loose-link feed chain. Arranged at opposite sides of and slightly below the chain sprocket 100 on parallel axes are guide sprockets or sheaves 102 and 103 which guide the feed chain 101 relative to the chain sprocket 100. The feed chain is herein in the form of a single continuous endless element and extends around the feed sprocket and the guide sprockets forwardly and rearwardly along the guiding frame as shown in Figs. 1 and 2, and passes around, at its forward end, a guide sprocket 104 or sheave 104 journaled on a horizontal stud 105 carried by the adjacent angle member 20 at the front end of the guiding frame. The chain 101 extends around the guide sprocket 104 and rearwardly along the side of the guiding frame and around a guide sprocket 106, rearwardly around a drive sprocket 107 and around a guide sprocket 108, the chain passing rearwardly from the sprocket 108 along the side of the guiding frame and around a guide sprocket 109 journaled on a horizontal stud 110 carried at the side of the rear end of the guiding frame. This chain passes upwardly around this guide sprocket 109 and forwardly beneath the guide sprocket 103, and is then engaged by the chain sprocket 100. The guide sprockets 106 and 108 and drive sprocket 107 are journaled on vertical axes and are supported by a frame 111 attached to the side of the guiding frame 2. As shown in Fig. 4, the drive sprocket 107 is keyed to a vertical shaft 112 suitably journaled within the frame 111, and also keyed to this shaft and driven thereby is a spur gear 113 meshing with the teeth of a gear segment 114 suitably attached to the frame 16 of the turntable mounting for the guiding frame 2. For holding the drive sprocket 107 against rotation there is provided a dog 115 having a tooth engageable with teeth 116 formed on the upper surface of the drive

sprocket, and this dog is pivotally mounted at 117 on the frame 111 and is provided with a suitable operating handle 118. A device is also provided for holding the sliding support for the cutting mechanism in its rear-most position on the guiding frame 2, and herein comprises, as shown most clearly in Fig. 12, an abutment member or pin 119 slidably receivable in an opening 120 formed in the adjacent angle member 20 of the guiding frame and having a suitable handle portion 121. The member 119 is connected by a chain 122 attached at 123 to the side of the guiding frame. When the pin is in the position shown in Fig. 12 the inner end thereof projects into the path of movement of the sliding support for the cutting mechanism thereby preventing forward movement of the cutting mechanism along the guiding frame 2. It will thus be seen that when the clutch 94 is connected the chain sprocket 100 may be driven in either of opposite directions under the control of the reverse friction 73, 74 at a relatively slow speed to swing the guiding frame 2 horizontally relative to the truck or to feed the cutting mechanism forwardly or rearwardly along the guiding frame at a relatively slow speed appropriate for cutting. When the stop pin 119 is in the position shown in Fig. 12, and the sliding support for the cutting mechanism is held against movement relative to the guiding frame, and the dog 115 is in its released position out of engagement with the teeth 116 on the chain sprocket 117, the chain 101 may be driven by sprocket 100 thereby causing rotation of the sprocket 107 and as a result driving the gearing 113, 114 to effect horizontal swinging movement of the guiding frame 2 relative to the truck; it being possible to swing the guiding frame in either of opposite directions under the control of the reverse frictions 73, 74. When it is desired to feed the cutting mechanism along the guideway 2 to effect its cutting operation, the stop pin 119 is removed from the opening 120 in the angle member 20 and the dog 115 is moved into its connected position thereby locking the sprocket 107 against rotative movement. Then, upon rotation of the sprocket 100 acting on the then stationary feed chain 101, the cutting mechanism is moved along the guiding frame 2. Movement of the cutting mechanism along the guideway may be effected at a slow speed in either of opposite directions under the control of the friction clutches 73, 74.

The truck propelling mechanism 4 for propelling the machine about the mine at a relatively high transport speed herein comprises a spur gear 125 (see Fig. 3) keyed to the lower end of the shaft 75. This spur gear meshes with an intermediate or idler gear 126 suitably journaled on a stub shaft carried by the sliding support 30, and this idler gear in turn meshes with the initial

driving gear 127 of the truck driving mechanism on the truck. It will thus be seen that when the sliding support 30 of the cutting mechanism is in its rearmost position on the 5 guiding frame, as shown in Figs. 2 and 3, the idler gear 126 on the sliding support 30 meshes with the initial driving gear 127 on the truck. When the gears 126, 127 are in meshing engagement, they are held in this 10 position by means of abutment pin 119 which, as previously mentioned, when inserted in the aperture 120 in the side of the guiding frame, projects into the path of the sliding support of the cutting mechanism 15 thereby preventing forward movement thereof along the guiding frame 2.

The driving connections between the initial driving gear 127 on the truck and the truck wheels will now be described. The 20 gear 127 is keyed to a vertical shaft 128 suitably journaled within a gear housing 129 supported by the truck frame. Fixed to the shaft 128 is a worm 130 meshing with a worm wheel 131 suitably journaled within 25 the gear housing. This worm wheel is connectible by a friction clutch 132 of the internal expanding type to a horizontal shaft 133 arranged transversely of the truck and suitably journaled within the gear housing. 30 The operating means for the clutch 132 includes an axially movable clutch applying member 134 having a cooperating pivoted shipper member 135 connected by a link to a pivoted operating handle 136. As shown in 35 Fig. 9, keyed to one end of the shaft 133 is a chain sprocket 137 connected by an endless chain 138 to a chain sprocket 139 secured to the rear truck wheel axle. The front and 40 rear truck wheel axles are connected in driving relation by a usual chain and sprocket connection 140, as shown in Fig. 2. It will thus be seen that when the clutch 132 is applied, the truck wheels may be driven at a relatively high transport speed from the motor 34 through the spur gearing 36, 37, 40, 42 and 44, bevel gear 69, one or the other of the reverse bevels 70, 71 (depending upon which of the reverse frictions 73, 74 is applied), shaft 72, shaft 75, spur gear 106, 107, 45 108, worm gearing 130, 131, transverse shaft 133, and the chain and sprocket connection 137, 138, 139 connected to the truck wheels.

The operating means for the various 50 clutches above referred to may assume various forms but are herein of the same type as those disclosed in the above mentioned Holmes application as also is the truck wheel brake and the adjustable front support for the guiding frame. The general method of 55 operation also is the same as that described in the Holmes application, and as the general mode of operation of a machine of the type disclosed is well known and as the mode of use of the improved feeding means for 60 the cutting mechanism and the means for

swinging the guiding frame relative to the support have been described above in detail, further description thereof is thought unnecessary other than to state that the guiding frame is suitably positioned relative to the truck prior to the cutting operation, the cutting mechanism is thereafter fed forwardly along the guideway to sump the cutter bar into the coal, the cutter bar is swung downwardly in its plane to effect its swinging cut, and thereafter fed rearwardly along the guideway to withdraw the bar from the coal. These and other uses and advantages of the improved mining machine will be clearly apparent to those skilled in the art. 70 75 80

While there is in this application specifically described one form which this invention may assume in practice, it will be understood that this form of the same is shown for purposes of illustration and that the invention may be modified and embodied in various other forms without departing from its spirit or the scope of the appended claims. 85

What I claim as new and desire to secure by Letters Patent is:

1. In a mining machine, a portable support, a guiding frame pivotally mounted on said support for horizontal swinging movement relative thereto, kerf cutting mechanism mounted on said guiding frame for bodily movement therealong including a pivoted kerf cutter swingable in a vertical plane at one side of said guiding frame and arranged to cut, during movement of said kerf cutting mechanism along said guiding frame, a kerf parallel to the direction of such movement, and motor operated devices for feeding said cutting mechanism relative to said guiding frame, for swinging said kerf cutter, and for swinging said guiding frame 90 95 100 105 relative to said support.

2. In a mining machine, a portable support, a guiding frame pivotally mounted thereon for horizontal swinging movement relative thereto, kerf cutting mechanism mounted on said guiding frame for bodily movement therealong including a pivoted kerf cutter swingable in a vertical plane at one side of said guiding frame and arranged to cut, during movement of said kerf cutting mechanism along said guiding frame, a kerf parallel to the direction of such movement, and motor operated devices for swinging said guiding frame relative to said support 110 115 120

and for feeding said cutting mechanism relative to said guiding frame including a flexible element connected to said guiding frame and a rotatable power driven member engaging said flexible member, and motor operated devices for swinging said kerf cutter about its pivot. 125

3. In a mining machine, a portable support, a guiding frame pivotally mounted on said support for horizontal swinging movement relative thereto, kerf cutting mecha- 130

nism mounted on said guiding frame for bodily movement therealong including a pivoted kerf cutter and a driving motor, and devices driven by said motor for swinging said guiding frame relative to said support and for feeding said cutting mechanism relative to said guiding frame including an endless flexible element and a rotatable power driven member engaging said flexible element.

4. In a mining machine, a portable support, a guiding frame pivotally mounted on said support for horizontal swinging movement relative thereto, kerf cutting mechanism mounted on said guiding frame for bodily movement therealong including a pivoted kerf cutter and a driving motor, and devices driven by said motor for swinging said guiding frame relative to said support and for feeding said cutting mechanism relative to said guiding frame including an endless flexible element guided on said guiding frame and a rotatable power driven member carried by said cutting mechanism and engaging said flexible element.

5. In a mining machine, a portable support, a guiding frame pivotally mounted on said support for horizontal swinging movement relative thereto, kerf cutting mechanism mounted on said guiding frame for bodily movement therealong including a pivoted kerf cutter and a driving motor, and devices driven by said motor for swinging said guiding frame relative to said support and for feeding said cutting mechanism relative to said guiding frame including an endless flexible element and a rotatable power driven member disposed on a horizontal axis and engaging said flexible element.

40 6. In a mining machine, a portable support, a guiding frame pivotally mounted on said support for horizontal swinging movement relative thereto, kerf cutting mechanism mounted on said guiding frame for bodily movement therealong including a pivoted kerf cutter and a driving motor, and devices driven by said motor for swinging said guiding frame relative to said support and for feeding said cutting mechanism relative to said guiding frame including an endless flexible element guided on said guiding frame and a rotatable power driven member disposed on a horizontal axis and carried by said cutting mechanism and engaging said flexible element.

65 7. In a mining machine, a portable support, a guiding frame pivotally mounted thereon for horizontal swinging movement relative thereto, kerf cutting mechanism mounted on said guiding frame comprising a sliding support and a kerf cutter pivotally mounted thereon, a motor carried by said sliding support, devices driven by said motor for swinging said guiding frame relative to said portable support and for sliding said

cutting mechanism support bodily relative to said guiding frame including an endless flexible element guided on said guiding frame at one side and at the ends thereof and a rotatable driving member disposed on a horizontal axis at one side of said sliding support and engaging said flexible element.

8. In a mining machine, a wheeled truck adapted to travel along a trackway, a guiding frame pivotally mounted on said truck for horizontal swinging movement relative thereto, devices for locking said guiding frame in its central longitudinal transport position on the truck, motor operated devices for swinging said guiding frame relative to said truck, kerf cutting mechanism mounted on said guiding frame for bodily movement therealong during the cutting operation and arranged to cut, during such bodily movement, a kerf in a plane parallel to the direction of such movement, the cutting mechanism including a rotatable power driven element, devices carried by said truck for driving the truck wheels and including an element driven by said power driven element, and means for holding said cutting mechanism on said guiding frame with said power driven element in driving engagement with said driving element on the truck.

9. In a mining machine, a wheeled truck adapted to travel along a trackway, a guiding frame pivotally mounted on said truck for horizontal swinging movement relative thereto, kerf cutting mechanism mounted on said guiding frame for bodily movement therealong and including a motor, devices driven by said motor for swinging said guiding frame relative to said truck and for moving said cutting mechanism relative to said guiding frame during the cutting operation, and truck wheel driving means including a driving element on said cutting mechanism and driven by said motor, a driven element on the truck and means for maintaining said elements in driving relation when said kerf cutting mechanism is in a predetermined position on said guiding frame.

10. In a mining machine, a wheeled truck adapted to travel along a trackway, a guiding frame pivotally mounted on said truck for horizontal swinging movement relative thereto, kerf cutting mechanism mounted on said guiding frame for bodily movement therealong and including a motor, devices driven by said motor for swinging said guiding frame relative to said truck and for moving said cutting mechanism relative to said guiding frame during the cutting operation, means for locking said guiding frame and cutting mechanism in a predetermined position on said truck, and truck wheel driving means including a driving element on said cutting mechanism and driven by said motor, a driven element on the truck and means for maintaining said elements in driving relation

when said kerf cutting mechanism is in aforesaid predetermined position on said guiding frame.

11. In a mining machine, a wheeled truck adapted to travel along a trackway, a guiding frame pivotally mounted on said truck for horizontal swinging movement relative thereto and extending a substantial distance in advance of the front truck wheels, kerf cutting mechanism mounted on said guiding frame for bodily movement therealong during the cutting operation, and arranged to cut, during such bodily movement, a kerf in a plane parallel to the direction of such movement, means for swinging said guiding frame relative to said truck and for moving said cutting mechanism relative to said guiding frame, means for locking said guiding frame and cutting mechanism in a predetermined position on said truck, and truck wheel driving means including a power driven element carried by said cutting mechanism and an element on said truck, said elements being in driving engagement when said guiding frame and kerf cutting mechanism are in aforesaid predetermined position.

12. In a mining machine, a wheeled truck adapted to travel along a trackway, a guiding frame pivotally mounted on said truck for horizontal swinging movement relative thereto, kerf cutting mechanism mounted on said guiding frame for bodily movement therealong and having cutting devices arranged to cut, during such longitudinal movement of said kerf cutting mechanism along said guiding frame, a kerf parallel to the direction of such movement, motor operated devices for swinging said guiding frame relative to said truck and for moving said cutting mechanism relative to said guiding frame, said frame swinging and cutting mechanism moving devices including common actuating means and means for holding an element of said actuating means stationary to effect one of aforesaid operations.

13. In a mining machine, a portable support, a guiding frame pivotally mounted on said support for horizontal swinging movement relative thereto, kerf cutting mechanism mounted on said guiding frame for bodily movement therealong during the cutting operation including a pivoted kerf cutter and a driving motor, and devices driven by said motor for swinging said guiding frame relative to said support and for moving said cutting mechanism at a cutting speed relative to said guiding frame including an endless flexible element and a rotatable power driven member engaging said flexible element.

14. In a mining machine, a portable support, a guiding frame pivotally mounted on said support for horizontal swinging movement relative thereto, kerf cutting mecha-

nism mounted on said guiding frame for bodily movement therealong during the cutting operation including a pivoted kerf cutter and a driving motor, and devices driven by said motor for swinging said guiding frame relative to said support and for moving said cutting mechanism at a cutting speed relative to said guiding frame including an endless flexible element guided on said guiding frame and a rotatable power driven member carried by said cutting mechanism and engaging said flexible element.

15. In a mining machine, a portable support, a guiding frame pivotally mounted on said support for horizontal swinging movement relative thereto, kerf cutting mechanism mounted on said guiding frame for bodily movement therealong during the cutting operation including a pivoted kerf cutter and a driving motor, and devices driven by said motor for swinging said guiding frame relative to said support and for feeding said cutting mechanism at a cutting speed relative to said guiding frame including an endless flexible element and a rotatable power driven member disposed on a horizontal axis and engaging said flexible element.

16. In a mining machine, a portable support, a guiding frame pivotally mounted on said support for horizontal swinging movement relative thereto, kerf cutting mechanism mounted on said guiding frame for bodily movement therealong during the cutting operation including a pivoted kerf cutter and a driving motor, and devices driven by said motor for swinging said guiding frame relative to said support and for feeding said cutting mechanism at a cutting speed relative to said guiding frame including an endless flexible element guided on said guiding frame and a rotatable power driven member disposed on a horizontal axis and carried by said cutting mechanism and engaging said flexible element.

17. In a mining machine, a portable support, a guiding frame pivotally mounted thereon for horizontal swinging movement relative thereto, kerf cutting mechanism mounted on said guiding frame comprising a sliding support and a kerf cutter pivotally mounted thereon, a motor carried by said sliding support, devices driven by said motor for swinging said guiding frame relative to said portable support and for sliding said cutting mechanism support bodily at a cutting speed relative to said guiding frame during the cutting operation including an endless flexible element guided on said guiding frame at one side and at the ends thereof and a rotatable driving member disposed on a horizontal axis at one side of said sliding support and engaging said flexible element.

18. In a mining machine, a wheeled truck adapted to travel along a trackway, a guid-

ing frame pivotally mounted on said truck for horizontal swinging movement relative thereto, kerf cutting mechanism mounted on said guiding frame for bodily movement therealong during the cutting operation and including a kerf cutter adjustable relative to said frame and a driving motor therefor, and devices driven by said motor for swinging said guiding frame relative to said truck, for 10 adjusting said kerf cutter, for moving said cutting mechanism at a cutting speed along said guiding frame and for driving the truck wheels.

19. In a mining machine, a portable support, a guiding frame pivotally mounted on said support for horizontal swinging movement relative thereto, kerf cutting mechanism mounted on said guiding frame for bodily movement therealong including a pivoted kerf cutter swingable vertically relative to said frame to make a shear cut and a driving motor therefor, and devices driven by said motor for swinging said guiding frame relative to said support and for moving said cutting mechanism relative to said guiding frame including an endless flexible element and a rotatable power driven member engaging said flexible element.

20. In a mining machine, a portable support, a guiding frame pivotally mounted on said support for horizontal swinging movement relative thereto, kerf cutting mechanism mounted on said guiding frame for bodily movement therealong including a pivoted kerf cutter swingable vertically relative to said frame to make a shear cut and a driving motor therefor, and devices driven by said motor for swinging said guiding frame relative to said support and for moving said cutting mechanism relative to said guiding frame including an endless flexible element guided on said guiding frame and a rotatable power driven member carried by said cutting mechanism and engaging said flexible element.

21. In a mining machine, a portable support, a guiding frame pivotally mounted on said support for horizontal swinging movement relative thereto, kerf cutting mechanism mounted on said guiding frame for bodily movement therealong including a pivoted kerf cutter swingable vertically relative to said frame to make a shear cut and a driving motor therefor, and devices driven by said motor for swinging said guiding frame relative to said support and for moving said cutting mechanism relative to said guiding frame including an endless flexible element and a rotatable power driven member disposed on a horizontal axis and engaging said flexible element.

22. In a mining machine, a portable support, a guiding frame pivotally mounted on said support for horizontal swinging movement relative thereto, kerf cutting mecha-

nism mounted on said guiding frame for bodily movement therealong including a pivoted kerf cutter swingable vertically relative to said frame to make a shear cut and a driving motor therefor, and devices driven by said motor for swinging said guiding frame relative to said support and for moving said cutting mechanism relative to said guiding frame including an endless flexible element guided on said guiding frame and a rotatable power driven member disposed on a horizontal axis and carried by said cutting mechanism and engaging said flexible element.

23. In a mining machine, a portable support, a guiding frame mounted on said support for horizontal swinging movement relative thereto about a vertical axis, kerf cutting mechanism mounted on said guiding frame for bodily movement therealong during the cutting operation, and motor operated devices for swinging said guiding frame relative to said support and for moving said cutting mechanism at a cutting speed relative to said guiding frame, said frame swinging devices including a motor movable with said cutting mechanism along said guiding frame, and connections driven by said motor including a gear mounted on said guiding frame and movable therewith and a stationary gear on said support with which said first gear meshes.

24. In a mining machine, a portable support, a guiding frame pivotally mounted on said support for swinging movement relative thereto, kerf cutting mechanism mounted on said guiding frame for bodily movement therealong during the cutting operation including a pivoted kerf cutter, motor operated devices for feeding said cutting mechanism at a cutting speed relative to said guiding frame to cut a kerf parallel to the direction of such feed and for swinging said kerf cutter, and motor operated devices for swinging said guiding frame relative to said support and including a frame swinging element on said support and arranged coaxially with the frame pivot.

25. In a mining machine, a portable support, a guiding frame pivotally mounted on said support for swinging movement relative thereto, kerf cutting mechanism mounted on said guiding frame for bodily movement therealong during the cutting operation and including a pivoted kerf cutter, motor operated devices for swinging said kerf cutter and for driving said cutting mechanism, and motor operated devices for feeding said cutting mechanism at a cutting speed relative to said guiding frame to cut a kerf parallel to the direction of such feed and for swinging said guiding frame relative to said support, said frame swinging devices including a frame swinging element arranged coaxially with the frame pivot.

26. In a mining machine, a portable sup-

port, a guiding frame pivotally mounted on said support for horizontal swinging movement relative thereto, kerf cutting mechanism mounted on said guiding frame for 5 bodily movement therealong during the cutting operation and including a pivoted kerf cutter, and motor operated devices for feeding said cutting mechanism at a cutting speed relative to said guiding frame to cut

10 a kerf parallel to the direction of such feed, for swinging said kerf cutter, and for swinging said guiding frame relative to said support, said frame swinging devices including a frame swinging element arranged coaxially with the frame pivot.

15 27. In a mining machine, a portable support, a guiding frame pivotally mounted on said support for horizontal swinging movement relative thereto, kerf cutting mechanism mounted on said guiding frame for bodily movement therealong during the cutting operation and including a pivoted kerf cutter and a driving motor, and devices driven by said motor for swinging said guiding

20 frame relative to said support and for feeding said cutting mechanism at a cutting speed relative to said guiding frame, said frame swinging devices including a frame swinging element arranged coaxially with the frame pivot.

25 28. In a mining machine, a wheeled truck adapted to travel along a trackway, a guiding frame pivotally mounted on said truck for horizontal swinging movement relative

30 thereto, kerf cutting mechanism mounted on said guiding frame for bodily movement therealong during the cutting operation and including a kerf cutter adjustable relative to said frame and arranged to cut, during

35 movement of said kerf cutting mechanism along said guiding frame, a kerf parallel to the direction of movement of said kerf cutting mechanism along said guiding frame, and motor operated devices for swinging said

40 guiding frame relative to said truck for adjusting said kerf cutter and for moving said cutting mechanism at a cutting speed along said guiding frame, said frame swinging devices including a frame swinging element arranged coaxially with the frame pivot.

45 29. In a mining machine, a wheeled truck adapted to travel along a trackway, a guiding frame pivotally mounted on said truck for horizontal swinging movement relative

50 thereto, kerf cutting mechanism mounted on said guiding frame for bodily movement therealong during the cutting operation and arranged to cut, during movement of said

55 kerf cutting mechanism along said guiding frame, a kerf parallel to the direction of movement of said kerf cutting mechanism along said guiding frame, and motor operated devices for swinging said guiding frame relative to said truck, for moving said cutting mechanism at a cutting speed along said

60 frame, a kerf parallel to the direction of movement of said kerf cutting mechanism along said guiding frame, and motor operated devices for swinging said guiding frame relative to said truck, for moving said cutting mechanism at a cutting speed along said

guiding frame and for driving the truck wheels, said frame swinging devices including a frame swinging element arranged coaxially with the frame pivot.

30 31. In a mining machine, a wheeled truck adapted to travel along a trackway, a guiding frame pivotally mounted on said truck for horizontal swinging movement relative thereto, kerf cutting mechanism mounted on said guiding frame for bodily movement therealong during the cutting operation and including a kerf cutter adjustable relative to said frame and arranged to cut, during movement of said kerf cutting mechanism along said guiding frame, a kerf parallel to the direction of movement of said kerf cutting mechanism along said guiding frame, motor operated devices for swinging said guiding frame relative to said truck, for adjusting said kerf cutter and for moving said cutting mechanism at a cutting speed relative to said guiding frame, said frame swinging and cutting mechanism moving devices including common actuating means and a frame swinging element actuated thereby and arranged coaxially with the frame pivot.

35 32. In a mining machine, a portable support, a guiding frame pivotally mounted on said support for swinging movement relative thereto, kerf cutting mechanism mounted on said guiding frame for bodily movement therealong during the cutting operation including a pivoted kerf cutter and a driving motor therefor, and devices driven by said motor for moving said cutting mechanism at a cutting speed relative to said guiding frame, for swinging said kerf cutter and for swinging said guiding frame relative to said support, said frame swinging devices including a frame swinging element arranged coaxially with the frame pivot.

40 33. In a mining machine, a wheeled truck adapted to travel along a trackway, a guiding frame pivotally mounted on said truck for horizontal swinging movement relative thereto, kerf cutting mechanism mounted on said guiding frame for bodily movement therealong during the cutting operation including a pivoted kerf cutter and a driving motor therefor, and devices driven by said motor for moving said cutting mechanism at a cutting speed relative to said guiding frame, for swinging said kerf cutter and for swinging said guiding frame horizontally relative to said support, said frame swinging devices including a frame swinging element arranged coaxially with the frame pivot.

45 34. In a mining machine, a wheeled truck adapted to travel along a trackway, a guiding frame pivotally mounted on said truck for horizontal swinging movement relative thereto, kerf cutting mechanism mounted on said guiding frame for bodily movement therealong during the cutting operation and

including a kerf cutter adjustable relative to said frame and a driving motor therefor, and devices driven by said motor for swinging said guiding frame relative to said truck, for adjusting said kerf cutter and for moving said cutting mechanism at a cutting speed along said guiding frame, said frame swinging devices including a frame swinging element arranged coaxially with the frame pivot.

34. In a mining machine, a portable support, a guiding frame pivotally mounted on said support for swinging movement relative thereto, kerf cutting mechanism mounted on said guiding frame for bodily movement therealong including a pivoted kerf cutter swingable vertically relative to said frame to make a shear cut in planes parallel to the direction of bodily movement of said kerf cutting mechanism along said guiding frame, motor operated devices for moving said cutting mechanism relative to said guiding frame and for swinging said kerf cutter, and motor operated devices for swinging said guiding frame relative to said support and including a frame swinging element arranged coaxially with the frame pivot.

35. In a mining machine, a portable support, a guiding frame pivotally mounted on said support for swinging movement relative thereto, kerf cutting mechanism mounted on said guiding frame for bodily movement therealong including a pivoted kerf cutter swingable vertically relative to said frame to make a shear cut in planes parallel to the direction of bodily movement of said kerf cutting mechanism along said guiding frame, motor operated devices for swinging said kerf cutter and for driving said cutting mechanism, and motor operated devices for moving said cutting mechanism relative to said guiding frame and for swinging said guiding frame relative to said support, said frame swinging devices including a frame swinging element arranged coaxially with the frame pivot.

36. In a mining machine, a portable support, a guiding frame pivotally mounted on said support for horizontal swinging movement relative thereto, kerf cutting mechanism mounted on said guiding frame for bodily movement therealong including a pivoted kerf cutter swingable vertically relative to said frame to make a shear cut in planes parallel to the direction of bodily movement of said kerf cutting mechanism along said guiding frame, and motor operated devices for feeding said cutting mechanism relative to said guiding frame, for swinging vertically said kerf cutter, and for swinging said guiding frame relative to said support, said frame swinging devices including a frame swinging element arranged coaxially with the frame pivot.

37. In a mining machine, a portable support, a guiding frame pivotally mounted on said support for horizontal swinging movement relative thereto, kerf cutting mechanism mounted on said guiding frame for bodily movement therealong including a pivoted kerf cutter swingable vertically relative to said frame to make a shear cut and a driving motor therefor, and devices driven by said motor for swinging said guiding frame relative to said support and for moving said cutting mechanism relative to said guiding frame, said frame swinging devices including a frame swinging element arranged coaxially with the frame pivot.

38. In a mining machine, a portable support, a guiding frame mounted on said support for horizontal swinging movement relative thereto about a vertical axis, kerf cutting mechanism mounted on said guiding frame for bodily movement therealong during the cutting operation, and motor operated devices for swinging said guiding frame relative to said support and for moving said cutting mechanism at a cutting speed relative to said guiding frame, said frame swinging devices including a motor movable with said cutting mechanism along said guiding frame and driving connections between said motor and a stationary element on said support, the latter being arranged coaxially with the frame pivot.

39. In a mining machine, a portable support, a guiding frame mounted on said support to swing horizontally relative thereto about a vertical axis, a sliding frame mounted on said guiding frame for bodily movement therealong, a kerf cutter pivotally mounted on said sliding frame to swing vertically relative thereto about a horizontal axis at right angles to the direction of bodily movement of said sliding frame along said guiding frame, motor operated devices for sliding said sliding frame relative to said guiding frame, motor operated devices for swinging said kerf cutter about its pivot relative to said sliding frame, and motor operated devices for swinging said guiding frame relative to said support and including a frame swinging element arranged coaxially with the frame pivot.

40. In a mining machine, a portable support, a guiding frame mounted on said support to swing horizontally relative thereto about a vertical axis, a sliding frame mounted on said guiding frame for bodily movement therealong, a kerf cutter pivotally mounted on said sliding frame to swing vertically relative thereto about a horizontal axis, motor operated devices for sliding said sliding frame relative to said guiding frame, motor operated devices for swinging said kerf cutter about its pivot relative to said sliding frame, and motor operated devices for swinging said guiding frame relative to said support.

said support, said devices including a common driving motor carried by said sliding frame and said frame swinging devices including a frame swinging element arranged 5 coaxially with the frame pivot.

In testimony whereof I affix my signature.

LEON E. SIMMONS.
